SWEEPER

Edwin D. Parker, Springfield, Ohio, and Edwin S. George, Bloomfield Hills, Mich.

Application March 7, 1940, Serial No. 322,728

3 Claims. (Cl. 15—83)

This invention relates generally to cleaning devices and more particularly to sweepers.

One of the objects of the present invention is to provide a new and improved sweeper capable of picking up dust and also being capable of picking up relatively large and heavy objects.

Another object of the invention is to provide a new and improved sweeper having a relatively low speed brush for picking up dust and small objects and having a relatively high speed brush for picking up large and heavy objects.

Another object of the invention is to provide a new and improved sweeper having a pair of rotary brushes separated by a readily removable refuse receptacle common to both of said brushes.

A further object of the invention is to provide a new and improved sweeper having flexible and adjustable ground engaging means to direct dirt and objects into the refuse receptacle of the sweeper and having provisions for adjusting the pressure of the brushes against the floor or other surface to be swept.

Other objects of the invention will become apparent from the following detailed description taken in connection with the accompanying drawings in which:

Figure 1 is a top plan view of the sweeper having parts broken away and in section to show certain details of construction;

Fig. 2 is a side elevational view of the sweeper;

Fig. 3 is a longitudinal central section of the sweeper;

Fig. 4 is a cross sectional view of the sweeper taken along the line and in the direction of the arrows 4—4 of Fig. 2;

Fig. 5 is a perspective view of a removable refuse receptacle of the sweeper; and

Fig. 6 is a diagrammatical side view of a modified form of sweeper.

Referring to the drawings by characters of reference, the sweeper shown includes a hollow casing which may be made of sheet metal having a top wall 10, side walls 11 and end or front and rear walls 12 and 13 respectively. The end or front and rear walls 12, 13 are continuations of the top wall and are rounded or curved downwardly to the bottom of the casing which is open, as shown. Intermediate the front and rear ends of the casing, the casing top wall 10 is provided with an opening which extends substantially entirely across the width of the casing and is closed by a readily removable refuse receptacle 14. This receptacle 14 divides the casing into two compartments comprising a front

compartment 15 and a rear compartment 16. In the front compartment 15 is mounted a relatively high speed rotary brush 17 and in the rear compartment 16 is mounted a relatively low speed brush 18, the axes of these brushes being substantially parallel to each other and extending transversely of the casing. In the present disclosure, the front brush 17 is smaller in diameter than the rear brush 18, but it will be understood that the brushes may be substantially the same diameter, if desired, or the front brush may be larger than the rear brush. The front brush 17 is rotated at a relatively high speed to obtain a lifting force to pick up heavy objects, while the rear brush 18 is rotated at a relatively low speed to avoid unnecessary stirring up of dust.

The front brush 17 may comprise a hollow spindle 20 on the outer periphery of which individual bristle holding members 20^a may be releasably and suitably secured to the spindle and the spindle may be fixed on a shaft 22. On wearing of the bristles, spacer members or shims may be provided between the members 20^a and the spindle 20 to bring the bristles into proper engagement with the floor or other surface to be swept. The opposite ends of the shaft 22 may project respectively through aligning apertures in the casing side walls 11 and be rotatably supported in bores in brackets 23 which brackets may be rigidly secured to the outer sides of the casing side walls 11. Similarly, the rear brush 18 may include a hollow spindle 24 on which separate bristle holding members 24^a may be suitably secured, and the spindle 24 may be secured to and over a shaft 25 having its opposite ends rotatably supported in bores of brackets 26 which may be rigidly secured to the outer sides of the casing. As in the brush 17, the bristle holders 24^a of the brush 18 may be released and shims may be provided between the holders and the spindle 24 to compensate for wear of the brush.

Referring now in detail to the receptacle 14, this receptacle is arranged to receive sweepings from both of the brushes and comprises a bottom wall 28, end walls 29, side walls 30, 31 and a top wall 32. Preferably, the receptacle top wall 32 is provided with outturned flanges 33 for seating on the upper surface of the casing top wall 10 and rigidly secured to the receptacle top wall 32 there may be provided one or more handles 34 for conveniently lifting and removing the receptacle from the sweeper casing. In its front and rear walls, the receptacle is provided

with inlet openings 35 and 36 respectively for the entrance of dirt and other sweepings from the brushes 17 and 18, these openings 35 and 36 extending substantially entirely the full length of the receptacle or coextensive with the brushes. Intermediate the top and bottom walls of the receptacle 14, an internal wall 37 forms the top wall of a refuse chamber 38, the internal wall 37 extending between and to the end walls 29 and extending downwardly from the upper edges of the opening to an apex. These angularly disposed walls serve to direct downwardly the dirt and other objects entering the chamber 38 of the receptacle.

Formed out of the casing top wall 10 is a downwardly extending flange 40 which extends transversely of the casing along and defines the forward edge of the opening in the casing top wall 10, this flange 40 having a lower border portion 41 thereof bent forwardly, as shown, to serve as a baffle and to direct dirt and other objects into the chamber 38. From the lower edge of the receptacle opening 35, a metallic guard 43 curves downwardly around the ends of the brush bristles, the guard being flanged at its opposite ends where it may be rigidly secured to the casing side walls 11 by bolts or by any other suitable means. The end flanges of the guard 43 are provided with horizontal slots 43^a to receive the bolts, the slots providing for adjustment of the guard with respect to the ends of the brush bristles. The guard 43 cooperates with the brush 17 to lift dirt and other objects which are later thrown off the brush through the opening 35 into chamber 38 and the lower edge of the guard 43 is preferably provided with an upwardly facing beveled surface to decrease resistance to the entrance of sweepings between the brush and the inner surface of the guard, the lower beveled edge of the guard being spaced above the ground or floor, as indicated at 44. Disposed below the metallic guard 43 is a second and flexible ground engaging guard 45, preferably a strip of rubber to prevent dirt and objects from being swept under the lower edge of the metallic guard 43. The rubber strip 45 may be suitably secured to a metallic strip 46, see Fig. 4, which may be movably supported near its opposite ends in slots 47 provided in brackets 48 which may be rigidly secured respectively to the casing side walls 11. As shown, the slots 47 are arranged such that the metallic strips 46, upon engaging a fixed object, will move rearwardly and upwardly to clear the object, thus avoiding damage to the sweeper. Mounted on each of the brackets 48 is a spring 49 arranged to urge the rubber guard downwardly into contact with the floor or ground, the springs 49 being respectively wrapped around pins 50 secured to respective brackets and one end of each spring being anchored and the other ends of the springs engaging in apertures provided in the metallic backing strip for the rubber strip 45. Extending downwardly from the lower edge of the opening 36 there is a metallic guard 46^a similar to the guard 43, the guard 46^a being coextensive with the brush 18 curving rearwardly such that the bristles engage or are in close proximity with the concave surface of the guard. The guard 46^a is provided with end flanges 46^b having horizontal slots 46^c to receive bolts which secure the guard to the side walls of the sweeper casing, the slots providing for adjustment of the guard with respect to the ends of the brush bristles. Secured to the guard 46^a 75

by a bracket or backing strip 47^a is a flexible ground engaging guard 48^a which is preferably a strip of rubber extending downwardly and rearwardly and having its lower edge beveled, as shown.

Intermediate the brushes 17 and 18, the sweeper is provided with a pair of ground wheels 50^a which may be of any suitable construction, preferably provided with rubber tires, and at the rear of the sweeper is provided a single and swivable ground wheel 51 which permits easy steering of the sweeper, the wheel 51 being vertically adjustable by a screw 51^a to aid in adjusting the pressure of the brush 18 against the floor or ground. The wheels 50^a may be mounted on separate, aligned, hollow spindles 52 which may be rotatably mounted on separate fixed shafts 53, and the shafts 53 may have inner end portions thereof rigidly secured respectively in hollow bosses of brackets 54 which may be rigidly secured to the casing side walls 11 by bolts or by other suitable means. The bolts are received in vertical slots 54^a provided in the brackets 54 to provide for vertical raising and/or 25 lowering of the sweeper casing to attain correct pressure of the brushes on the floor.

Integral or otherwise secured to each of the spindles 52 is a pair of spaced sprockets 55 and 56, the sprockets 55 being separately connected by chains 56^a respectively to sprockets 57 secured to the outer ends of the front brush shaft 22. The other or inner sprockets 56 are connected by chains 57^a respectively to drive idler sprockets 58 on stub shafts which are mounted on the 30 casing side walls 11 near the rear end of the casing, and intermediate the wheel sprockets 56 and the idler sprockets 58 the chains respectively drive sprockets 60 provided on opposite ends of the rear brush shaft 25. It will be seen that the idler gears 58 provide for rotation of the rear brush 18 in the opposite direction with respect to the rotation of the front brush 17. In Fig. 6 there is shown a sweeper which, instead of having two pairs of drive chains connecting the ground wheels and brushes, has but one pair of continuous chains, designated by the numeral 45 63. A handle for pushing the sweeper may have side members 61 which may be suitably secured to the casing side walls 11. On each side of the sweeper casing the sprockets and chains may be provided with a housing 62 which may be secured to the sweeper casing in any suitable manner.

At times, it may be desired to sweep along the edge of a dock or other platform where, in order for the brush to reach, the outer ground wheel would have to overhang the dock or platform and, to this end, a wheel or caster 65 is provided at the front of the casing to support the same under the above condition. If desired, the front 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 jects while the front brush 17 will sweep up heavy objects. When desired the receptacle 14 may be readily lifted out of the sweeper casing and the dust, dirt and articles therein may be dumped out of the receptacle through the openings 35 and 36.

While we have shown and described our invention in detail it is to be understood that the same is to be limited only by the appended claims for many changes may be made without departing from the spirit and scope of the invention.

What we claim is:

1. In a sweeper, a casing having front and rear ends, a rotary brush disposed within said casing adjacent one end thereof, another rotary brush disposed within said casing adjacent the other end thereof and spaced from said first-named brush, a receptacle disposed within said casing between said brushes and having oppositely disposed inlets for respective brushes, ground wheels supporting said casing, and means operatively connecting said ground wheels and both of said brushes and so arranged to rotate one brush at a relatively high peripheral speed and the other brush at a relatively low peripheral speed.

2. In a sweeper, a casing, a rotary brush mounted in said casing, another rotary brush mounted in said casing in spaced relation to said first-named brush, a receptacle disposed within said

casing between said brushes and having oppositely disposed side walls in close proximity to the respective brushes, an inlet formed in each of said walls opposite the respective brush, ground wheels supporting said casing, and means operatively connecting said ground wheels and said brushes and so arranged to rotate one brush at a relatively high peripheral speed and the other brush at a relatively low peripheral speed.

3. In a sweeper having ground supporting means, a casing carried by the supporting means and having front and rear ends, a rotary brush mounted within said casing adjacent said front end, a second rotary brush mounted within said casing adjacent said rear end, said casing having a wall provided therein with an opening between said brushes, a receptacle removably carried within said opening and extending transversely of said casing, elongated inlets formed in the front and rear walls of said receptacle opposite said brushes and between the upper and lower ends of said receptacle, and a wall carried by said front and rear walls of said receptacle at the upper ends of said inlets and declined from said upper inlet ends toward an apex disposed below and intermediate same.

EDWIN D. PARKER.
